Inventor:

W. R. UCHTMANN,
By *Henry C. Johnson, Attorney*

UNITED STATES PATENT OFFICE.

WEET R. UCHTMANN, OF BOSTON, MASSACHUSETTS, ASSIGNOR OF ONE-HALF TO OLE M. DAHL, OF BOSTON, MASSACHUSETTS.

BOTTLE-SEAL.

1,155,773.

Specification of Letters Patent.

Patented Oct. 5, 1915.

Application filed April 13, 1915. Serial No. 21,131.

To all whom it may concern:

Be it known that I, WEET R. UCHTMANN, a subject of the Emperor of Germany, and a resident of Boston, county of Suffolk, and 5 Commonwealth of Massachusetts, have invented an Improvement in Bottle-Seals, of which the following description, in connection with the accompanying drawings, is a specification, like characters on the drawings representing like parts.

10 This invention relates to bottles or other similar containers, and its object is to provide an improved and novel seal therefor that will be so mutilated by withdrawing the closure from the container that the seal 15 will show at a glance that the original closure has been withdrawn.

For a clear understanding of my invention, I have herein described and illustrated 20 one embodiment thereof, and in the drawings Figure 1 is a side elevation of a bottle, partially broken away, provided with the seal; Fig. 2, a vertical section thereof on the line 2—2, Fig. 1; Fig. 3, a plan of the seal in position on a bottle neck, and Figs. 25 4 and 5, respectively, different side elevations of another manner of using the seal on standard forms of bottles.

The embodiment of my invention illustrated, comprises a closure receiving ring-like member 1 of any suitable material as metal, glass, wood, etc., of suitable size to fit conveniently the neck 2 of the bottle. If desired, the lower inner edge 3 of the ring 30 may be provided with a depending flange 4 adapted to seat on a beveled edge 5 of the inner face of the neck 2, to act to retain the ring 1 on its seat during the bottling operation, wherein the cork or closure is usually 35 driven in by a machine for that purpose. On one edge at least the ring 1 may be provided with a preferably slender and downwardly extended tongue 6 of some fragile material, as glass, the tongue being enlarged 40 somewhat toward its lower end as at 7. The tongue is adapted to engage, at a suitable point thereon, the outer edge of the bottle neck, as the lip 8. This enlarged end of the tongue is, in this case, adapted to be received by a pocket 9 in the outer edge of the lip 8, the tongue 6 itself being received by a slot 10 in the fin 11 formed over the pocket to insure the more certain engagement of the lip by the tongue.

45 I prefer to so construct the ring 1 that the

upper opening of the passage therethrough for the cork will be a little smaller than the opposite or lower opening. Under these conditions the cork will expand and fit the opening tightly after it is inserted, being a 60 little larger in diameter through the body thereof than at its upper extreme end. When the cork is withdrawn, the enlarged diameter thereof below the opening of the ring 1 will tend to wrench the ring 1 from its seat, 65 thereby rupturing the fin 11 and tongue 6, or one of them, and thus indicate clearly that the seal has been broken and that the contents of the bottle may have been withdrawn. To still further insure the breaking 70 of the seal and fin 11 upon withdrawal of the cork, I prefer to form upon or secure to the inner wall 12 of the ring 1, one or more teeth 13 preferably downwardly extended, to engage the cork as it is withdrawn, and make it difficult to withdraw the same without rupturing the seal and fin.

In Fig. 4 I have illustrated a modified form of my invention wherein the ring 1 is provided with one or more depending 80 tongues 6 at suitable points thereon. These tongues are each provided with an enlarged end 7 adapted to engage the lower edge of the lip 8 of the usual bottle neck 2, in such manner that the withdrawal of the cork 85 from the neck will lift the ring 1 sufficiently from its seat to cause a rupture of the several tongues 6. This form of my invention is particularly adapted for use where it is desired to use the seal on standard forms of 90 bottles making it unnecessary to use a special bottle therefor. In this case the flange may be on the outer edge of the ring 1, and to permit the ring to be seated on the neck of the bottle and also permit the tongue ends 7, 95 7, to be positioned beneath the lower edge 13 of the lip 8, I have shown a portion of the flange 4 cut away so that one may slide the ring 1 into position, and to provide an engaging surface for the tongue ends 7, 7, one 100 may bevel the lower edge of the lip slightly as at 14, 14, so that the ends 7, 7, may slide beneath said bevel or cam surface as the ring 1 is seated. In use the ring 1 is first placed in position on the bottle neck with 105 the tongue 6 and its enlarged lower end 7 in position, as shown in Fig. 2. The cork or other closure 12 is then inserted in the usual manner.

110 While I have herein described and illus-

trated one embodiment of my invention, it should be understood that many detail changes thereof may be made all within the spirit of the invention and scope of the appended claims.

Claims:

1. A bottle seal comprising a ring and a neck engaging fragile tongue thereon adapted to be fractured by withdrawal of the stopper.
2. A bottle seal comprising a ring and a neck engaging fragile tongue thereon of varying dimensions in cross section adapted to be fractured by withdrawal of the stopper.
3. A bottle seal comprising a ring, a flange thereon, and a neck-engaging fragile tongue on the ring.
4. A bottle seal comprising a ring, cork engaging teeth thereon, and a neck-engaging fragile tongue on the ring.
5. The combination of a ring having a neck-engaging fragile tongue adapted to be

fractured by withdrawal of the stopper, and a bottle having a pocket for receiving said tongue end.

6. The combination of a ring having a neck-engaging fragile tongue adapted to be fractured by withdrawal of the stopper, and a bottle having a beveled face for receiving the tongue end thereon.

7. A bottle seal comprising the ring 1 having the tongue 6 with enlarged end 7 adapted to be engaged by the bottle neck.

8. The combination with the ring 1 having the tongue 6 with enlarged end 7, of the bottle provided with the pocket 9 and slotted fin 11.

In testimony whereof, I have signed my name to this specification, in the presence of two subscribing witnesses.

WEET R. UCHTMANN.
